MAGAZINE FOR HOLDING A SUPPLY OF FASTENERS FOR A FASTENER DRIVING TOOL

Andrew I. Yohana, Des Plaines, Ill., assignor to
Duo-Fast Corporation, Franklin Park, Ill.

Filed Apr. 29, 1974, Ser. No. 464,911

Term of patent 14 years

Int. Cl. D8—05

U.S. CL. D8—76

Fig. 2

Fig. 3

Fig. 1

FIG. 1 is a side view of a magazine for holding a supply of fasteners for a fastener driving tool embodying my new design;

FIG. 2 is a front view of the magazine;

FIG. 3 is a top view of the magazine;

FIG. 4 is a rear view of the magazine;

FIG. 5 is a bottom view of the magazine; and

FIG. 6 is a side view of the magazine showing the side opposite to that shown in FIG. 1 and showing the hinged door in closed position.

I claim:

The ornamental design for a magazine for holding a supply of fasteners for a fastener driving tool, substantially as shown and described.
